UNITED STATES PATENT OFFICE

GEORGE C. PECK, OF GRANITE CITY, ILLINOIS

RADIATOR CLEANER

Application filed October 20, 1928. Serial No. 313,873.

This invention relates to a device for cleaning the radiators of automobiles and the like. The usual method hitherto employed for cleaning these radiators has consisted in removing the radiator from the automobile and boring a hole in the bottom of the radiator at the side remote from the outlet stem. Compressed air, together with tap water under the usual pressure of a city water supply system, was then introduced into the radiator through the outlet stem at the lower portion of the radiator through a rubber hose connection thereto, and compressed air was also introduced into the radiator through the aforesaid hole by means of a suitable connection thereto, the purpose having been to cause the air to rise through the water tubes at both sides of the radiator, thereby loosening the impacted material or deposits from the interior of all the tubes equally, the loosened deposits ascending through the radiator with the flowing water and being discharged therefrom with the water through the inlet stem or the radiator cap opening. After the completion of the cleaning operation, the hole that had been made in the bottom of the radiator had first to be closed by soldering a plate thereover, prior to replacing the radiator in its position on the automobile.

Accordingly, the present invention aims to provide means whereby the radiator may be cleaned internally without first having to remove it from its position in the automobile; without having to bore the aforesaid hole in the bottom and subsequently having to re-close it; and without having to lose time in making inconvenient soldered or hose connections to the hole in the bottom of the radiator or to the outlet stem. Other objects and advantages will appear in the course of the following description of an illustrative embodiment of the invention.

In the accompanying drawings forming part of this specification, in which like numbers of reference denote like parts wherever they occur,

Figure 1 is a rear elevation of an automobile radiator, showing the cleaner of this invention attached to the outlet stem thereof;

Figure 2 is a fragmentary sectional view of

the cleaner, taken on the line 2—2 in Figure 3;

Figure 3 is a view of the detached cleaner, looking at the side that is presented to the outlet stem or pipe of the radiator, and with parts broken away; and

Figure 4 is a sectional view taken on the line 4—4 in Figure 1.

The illustrative embodiment comprises a conduit-bearing body or casing 1 that serves as a closure member for the open end of the hollow stem or outlet pipe 2 of the automobile radiator 3. The casing 1 is clamped against the end of the pipe 2 by means of a clamping frame 4, comprising an annular portion or ring 5 that embraces the pipe 2 and a U-shaped portion 6 whose ends rise from opposing portions of the ring 5. A plurality of set screws 7 extend radially through and in threaded relation to the ring 5 at equal angular intervals, and are adjusted to clamp against the wall of the pipe 2. A set screw 8 threads through the intermediate portion 9 of the U-shaped portion 6 that extends behind the member 1, and is adjusted to force the casing 1 against the open end of the pipe 2. An annular gasket or washer 10, preferably of rubber, is interposed between the end of the pipe 2 and the seating face 11 of the casing 1 to facilitate the making of a leak-proof connection.

A plurality of threaded openings 12, 13 and 14 are formed in the annular wall 15 of the casing 1. A short threaded pipe or nipple 16 passes in threaded relation through the intermediate opening 13, and is preferably secured tightly by means of a locknut 17. The inner end of nipple 16 threads tightly into the short arm 18 of a pipe elbow 19, the other arm 20 of which extends through a sleeve portion 21 that rises from the edge of a central opening 22 in the seating wall 11. The outer end of arm 20 is threaded exteriorly to receive the internally threaded end 23 of a flexible conduit or hose 24. Conduit 24 passes through pipe or outlet stem 2 into the interior of the radiator 3, as best shown in Figure 4, and then extends along the bottom of the radiator toward the side remote from the stem 2, as best shown in Figure 1, and

then preferably terminates in a non-flexible up-turned end 25. A nipple 26 is threaded into the opening 12. Nipples 16 and 26 are connected to respective valves or cocks 27 and 28 through the intermediation of pipe unions 29 and nipples 30. Valves 27 and 28 are preferably formed in a single casting or casing 31 and both communicate with a common or single inlet conduit 32, having a nipple 33 threaded thereinto. A short pipe 34 threads into the opening 14, and a sleeve 35 threads on the outer end of pipe 34. The outer end of sleeve 35 is threaded at 36 to fit a water hose connection.

15 With the device attached to the radiator as shown in Figures 1 and 4, a conduit leading from a source of compressed air is connected to the nipple 33; and a hose leading from a source of water under a suitable pressure is connected to the nipple 35. Valves 27 and 28 are opened to admit air from their common conduit 32 into their respective conduits, 16 and 26, and the tap to which the water hose is connected is opened to admit water into the conduit 34. Water from pipe 34 and air from pipe 26 enter the chamber in the casing 1 and discharge therefrom through opening 22 and sleeve 21 to enter the hollow outlet stem or pipe 2 and the radiator 3. The air rises in the passage of the pipe 2 and ascends through the water in those tubes of the radiator that are juxtaposed to the passage of the pipe 2. However, air also passes through the pipe 16, the elbow 19, and the flexible conduit 24, emerging from the end 25 of said flexible conduit and bubbling up through the water tubes that are disposed thereover, or on that side of the radiator remote from the pipe 2. It will be observed that the flow of water is controlled independently of the flow of air, and that the valves 27 and 28 are operated independently of one another to regulate the flow of air as may be required at opposite sides of the radiator. The use of this device makes it unnecessary to remove the radiator and to bore a hole in its bottom in order to clean both sides of the radiator in an equally thorough manner; and the device can be easily attached or detached without having to make special or soldered connections. The device is also useful for cleaning the water jacket of an internal-combustion engine, the flexible conduit 24 serving to distribute the air to parts remote from the inlet opening of the jacket to which the device is connected.

Having thus fully described this invention, I hereby reserve the benefit of all changes in form, arrangement, order, or use of parts, as it is evident that many minor changes may be made therein without departing from the spirit of this invention or the scope of the following claims.

I claim:

1. A cleaner of the character described comprising a casing having an opening, said

casing being adapted to close a passage to a chamber to be cleaned and adapted to discharge thereinto through said opening, a pair of conduits for conveying gas and liquid, respectively, into the interior of the casing, and a conduit borne by the casing and extending therethrough and projecting through said opening to a point remote therefrom.

2. In a device of the character described, a casing provided with an exit opening for fluid and a pair of entrance openings for receiving fluids, a conduit having a diameter smaller than that of said exit opening and extending through the casing but being out of communication with the interior of the casing and extending through said exit opening, and a second conduit branching off from the first conduit and terminating at one of the said entrance openings.

3. In a device of the character described, a casing having an exit opening and three entrance openings, said casing being adapted to be connected to a passage to a chamber with said exit opening opening into said passage, a conduit extending through one entrance opening and through said casing and projecting through said exit opening in spaced relation to the walls of said exit opening, means connected to that end of said conduit which projects through said exit opening and adapted to extend through said passage and into said chamber to convey a gas to said chamber, a second conduit connected within another entrance opening to convey a gas into said casing and a third conduit connected with the remaining entrance opening to convey a liquid into said casing.

4. A cleaner of the character described comprising a casing adapted for connection to a passage to a chamber, said casing having an opening to discharge into said passage and being provided with three conduits, means for controlling each of said conduits independently of the others, one of said conduits being adapted to convey liquid into the casing, another to discharge gas into the casing, and the other being extended through the casing and of a length to extend into the chamber to a remote point thereof to discharge gas into the chamber at a point remote from said passage.

In testimony whereof I hereunto affix my signature.

GEORGE C. PECK.
